STRAINER

William A. Gorden, Shelton, Conn., assignor to
 Farrel-Birmingham Company, Incorporated,
 Ansonia, Conn., a corporation of Connecticut

Application February 20, 1931, Serial No. 517,172

7 Claims. (Cl. 146—174)

This invention relates to strainers and aims to provide certain improvements therein.

In the working of rubber compounds it is customary to force the plastic compound through so-called strainers which are provided with a multiplicity of fine openings, the compounds being forced through the strainers under very considerable pressure. In such straining machines pressure is put upon the plastic compounds usually by a pressure screw, which receives the material from a hopper and conveys it along a cylinder to the end thereof where the strainer head is mounted. In some of the prior constructions the strainer head has been provided with perforations on its end face. The area of such end face is, however, limited, and for this reason in some constructions the strainer head has been constructed as a cap with perforations in its side or cylindrical walls so that a larger area of strain- 10 er surface is available. Neither of these expedients has resulted in securing the desired output, since the compound is stiff and requires a very considerable pressure to force it through the fine openings required, and in each of the cases mentioned the pressure on the compound has been exerted largely in the direction of length of the screw.

According to the present invention I provide a construction which in its preferred form utilizes 30 a strainer having lateral openings, and I provide means for imparting to the compound a pressure which is very largely transverse to the axis of the pressure screw. The means for accomplishing this purpose are best located at the end of the 35 pressure screw and within the strainer head, although other constructions are not excluded. The simplest form of the device comprises a lateral forcing means formed integrally with the screw at the end thereof, so that it is driven by 40 the screw. The invention also includes certain other features of construction which will be hereinafter more fully described.

In the drawings, which illustrate one form of the invention,—

45 Figure 1 is a side elevation of a straining machine, embodying the preferred form of the invention.

Fig. 2 is an enlarged section, taken on the line 2—2 in Fig. 1.

50 Fig. 3 is an enlarged longitudinal section of the screw and part of the machine.

Fig. 4 is a section of the strainer head taken on the line 4—4 in Fig. 3, and still further enlarged.

55 Fig. 5 is a view on a smaller scale of the screw detached from the machine.

Referring to the drawings, let A indicate the bed of the machine having a front housing B, the interior of which is formed as a cylinder C, which is properly waterjacketed, the cylinder C being preferably constructed separate from the housing and adapted to fit therein. D is the pressure screw which has a portion extending under a hopper E, as best seen in Fig. 3, the shaft of the screw extending backwardly for a suitable drive indicated as comprising a large gear F turned by a small gear G mounted upon a shaft H which is rotated by a larger gear I, meshing with a pinion J mounted upon a shaft K, which receives motion from any suitable source of power transmitted through a shaft L which is connected with the shaft K through a flexible connection M. At the rear of the hopper the pressure screw shaft is provided with a pinion N, meshing with a similar pinion O mounted upon a counter-shaft P which extends forwardly and turns a feed roll Q located in the hopper E of the machine. By reference to Fig. 2, it will be seen that I provide a scraper R which clears the face of the feed roll Q, the scraper R being yieldingly mounted upon a plate S, but being normally held in engagement with the feed roll Q by a spring T surrounding a shaft U which is screwed into the scraper.

The form of screw which I prefer to utilize is of the type which contacts closely with its cylinder, and is so shaped as to provide the maximum degree of compression in lines which are parallel with the axis of the screw, or in other words, one which is adapted to feed the material forward under pressure to the best advantage. I have hence shown a screw with a thread whose front walls are substantially transverse to the axis of the screw.

The strainer section of the machine, which is that to which my invention chiefly relates, is indicated as a whole by the reference letter V. This strainer section comprises a strainer W having a multiplicity of lateral openings distributed throughout its circular wall, so as to provide lateral egress of the material. The important feature of the invention, however, is the provision of a forcing member X, which is designed to receive the compound as it is compressed axially by the screw, and to force it mechanically in a radial direction. The means for accomplishing this purpose are subject to considerable modification, but in the drawings I have illustrated the form which I prefer to use.

In this form I provide one or more blades Y, 110

each of which has a curved face Z, which in connection with the strainer provides a wedge-shaped space A', the base of which leads as the screw is rotated, and the apex of which follows. This is best shown in Fig. 4, wherein the section X is illustrated as rotating in the direction of the arrow. One such blade might be used, but I prefer two, as shown, or more, the blades being symmetrically arranged so as to equalize the reaction thrusts. It will be observed that the material which is being piled up in the end of the cylinder by the main portion of the screw D is, when it reaches the strainer head, subjected to the wedging action of the blades Y so that it is given a powerful radially outward compression, thus forcing it through the strainer directly and positively by mechanical means, as distinguished from the pressure of the material behind it, as is now the case. It is useful if the hub supporting the blades Y be formed with a tapered surface, such as shown at B' (Fig. 3) by which the material is guided more or less into a radial path between the blades.

The details of the strainer proper are a subordinate feature of the invention. I have shown the strainer casing in the form of a cap C', the multiplicity of holes or outlets D' being more or less radially arranged. The cap C' is shown as connected to the housing B by a ring E' which 30 overlies a flange on the cap, and is itself held in place by bolts F'. In Fig. 4 I have shown the construction I prefer to use for the actual screening section, which construction comprises a three-part lining extending along the inner side of the cap C', this lining comprising two cylinders of relatively coarse meshed wire screening designated by the reference letters G' and H'. Interposed between the two is a much finer screen, the number of meshes of which to the square inch depends upon the character of the material to be strained. This intermediate screen is lettered I'. This construction provides a support for what may be termed the actual screen, namely, the sleeve I', both inside and outside.

It is, of course, understood that the invention is useful in straining crude rubber or any other materials which may require similar treatment.

While I have shown and described one form of the invention, it will be understood that I do not 50 wish to be limited thereto, since various changes

may be made therein without departing from the spirit of the invention.

What I claim is:

1. In a strainer for rubber compounds or the like, a rotatable forcing member adapted to receive material, fed under axial pressure, and to force said material laterally through lateral straining means, said forcing member comprising longitudinally disposed blades on a tapered hub having its minimum diameter at the receiving extremity thereof, the taper of the hub being substantially free of laterally disposed convolutions. 80
2. A device according to claim 1 in which the hub is concavely tapered. 90
3. A device according to claim 1 in which the blades are disposed upon the tapered portion of the hub. 85
4. A device according to claim 1 in which the inner portions of the leading faces of the blades are in advance of the outer portions thereof in the path of rotation. 95
5. A device according to claim 1 in which the leading faces of the blades are convexly curved, the inner portions of said faces being in advance 100 of the outer portions thereof in the path of rotation.
6. A device according to claim 1 in which the blades are substantially parallel to the axis of the hub. 105
7. A straining mechanism for rubber compounds or the like comprising a heavy casing having a cylindrical wall, a straining sleeve at the end of said cylinder, a rotatable elongated conveyor member mounted within said cylinder and 110 sleeve, the portion of said conveyor member within the cylinder having substantially laterally disposed convolutions adapted to force material longitudinally toward the straining sleeve, the portion of said conveyor member within the 115 straining sleeve having its hub flared to its maximum diameter toward the extreme end thereof and having longitudinally disposed blade-like protuberances on said flared portion whereby said flared portion and blade-like protuberances operate to guide and force the material outwardly 120 through the straining sleeve, the flared portion of the hub being substantially free of laterally disposed convolutions. 125
